UNITED STATES PATENT OFFICE.

JACQUES WORTH, OF PARIS, FRANCE.

DESIGN FOR A POWDER BOX.

Application filed June 17, 1924. Serial No. 9,886. Term of patent 14 years.

To all whom it may concern:

Be it known that I, JACQUES WORTH, citizen of the Republic of France, residing at Paris, France, have invented a new, original, and ornamental Design for a Powder Box, of which the following is a specification, reference being had to the accompanying drawing, forming part thereof.

In the drawing:

Fig. 1 is an elevation of the box closed;

Fig. 2 is a top view of the closed box, showing the cover or lid thereof;

Fig. 3 is a view of the box from underneath, showing the outer side of the bottom thereof.

I claim:

The ornamental design for a powder box, as shown.

In testimony whereof I affix my signature.

JACQUES WORTH.
